Term of patent 14 years

(Cl. D54—2)

Fig. 1.

Fig. 2.

Fig. 3.

FIG. 1 is a front elevation view of an architectural fretwork embodying my new design, it being understood that the design is repeated as indicated;

FIG. 2 is a sectional view taken along the line 2—2 of FIG. 1, looking in the direction of the arrows; and

FIG. 3 is a sectional view taken along the line 3—3 of FIG. 1, looking in the direction of the arrows. The broken lines on the drawings are disclosed for illustrative purposes only.

The appearance of the opposite sides of the design is the same as that of the face thereof illustrated in FIG. 1.

I claim:

The ornamental design for an architectural fretwork, substantially as shown and described.
